MANUFACTURE OF SHOES AND SHOE BOTTOM UNITS

Clifford Roberts, Winchester, Mass., assignor to
United Shoe Machinery Corporation, Paterson,
N. J., a corporation of New Jersey

Application July 27, 1938, Serial No. 92,790

6 Claims. (Cl. 12—142)

This invention relates to improvements in shoes and shoe bottom units and to improvements in methods of making shoes.

In United States Letters Patent No. 2,065,463, granted December 22, 1936, upon application of John M. Whelton, there is disclosed a shoe bottom unit comprising an insole, a heel and shank reinforcing piece which is secured to the lower or lasting side of the insole and which entirely covers the heel and shank portions thereof, and a shank stiffener which is interposed between the reinforcing piece and the insole. The reinforcing pieces for such insole units are commonly made of fiberboard or similar stiff material of laminated formation and in the manufacture of a shoe embodying such an insole unit it is a common practice to secure the margin of the upper in overlasted position upon the fiber reinforcing piece by means of cement. While a sufficiently firm attachment of the upper to the outermost layer of the fiberboard is established in most cases, it sometimes happens that one or more of the fiberboard layers become separated from the rest of the reinforcing piece as a result of the strains to which the bottom of the shoe is subjected while it is being worn and in such cases the attachment of the insole unit to the upper becomes unduly weakened.

For the purpose of avoiding such an undesirable condition the reinforced insole unit herein illustrated is of improved construction having a reinforcing piece of fiberboard or similar material at the lower or lasting side of its shank portion which is substantially narrower than the shank portion of the insole and is arranged to expose marginal surfaces of substantial width at opposite sides of the reinforcing piece for the reception of lasting cement thereby enabling the shoe upper to be cement-lasting directly to the shank portion of the insole itself. Thus, by employing an insole of leather or other material which is not of laminated formation (or which, if laminated, has its component layers so firmly secured together that there is little if any tendency for them to become separated) any inherent weakness in the attachment of the upper to the insole unit is positively insured against. Preferably, and as herein shown, the reinforcing piece, while narrower than the shank portion of the insole, is nevertheless sufficiently wide to provide for a sufficient width of bonding area between the reinforcing piece and the insole to insure that the desired transverse curvature of the shank portion of the unit shall be maintained. Moreover, as illustrated, the opposite edges of the narrow

portion of the reinforcing piece are cut substantially perpendicular to the surfaces of the piece so as to constitute upstanding lasting shoulders for deflecting upwardly the surplus lasting allowance of the upper and thus to facilitate subsequent trimming of the latter.

In making a shoe embodying my improved reinforced insole unit the upper, after being assembled with an insole unit on a last, is lasted over the exposed insole surface in the shank portion of the unit and secured in overlasted position thereon preferably by means of cement with the surplus portions of its lasting allowance standing beside the opposite edges of the reinforcing piece, the upstanding portions of the upper are trimmed substantially flush with the exposed surface of the reinforcing piece and with the outer surfaces of the rest of the overlasted upper, and an outsole is laid and its shank portion secured by means of cement to the overlasted portions of the upper including the trimmed edges of the latter. Thus, not only is the upper secured to the insole unit in such a way that its attachment is not liable to be subsequently weakened, but a substantially continuous surface is provided in the shank portion of the shoe bottom for the reception of an outsole and a secure bond of adhesion is established between the outsole and the shoe bottom.

Invention is also to be recognized as residing in certain improved features of shoe construction resulting from the practice of the above-described method.

The invention will now be explained with reference to the accompanying drawing, in which—

Fig. 1 is a perspective view of my improved insole unit;

Fig. 2 is a sectional view thereof taken along the line II—II of Fig. 1;

Fig. 3 is a cross-sectional view of the shank portion of the insole unit;

Fig. 4 is a fragmentary cross-sectional view of a shoe in the course of construction, the shoe having embodied therein my improved insole unit;

Fig. 5 is a view similar to Fig. 4 but illustrating a further stage in the manufacture of a shoe; and

Fig. 6 is a fragmentary cross-sectional view of the completed shoe.

Referring to the drawing, my improved insole unit comprises a full-length insole 10 preferably of leather or other non-laminated material to which lasting cement will readily adhere, a heel and shank reinforcing piece 12 which may be composed of fiberboard or similar stiff material 55

and which is secured by means of cement to the insole, and a metallic shank stiffener strip 14 which is interposed between the reinforcing piece and the insole. As shown, the shank stiffener 14 has the usual longitudinal curvature and the shank portions of the reinforcing piece 12 and the insole 10 are curved longitudinally to correspond to the longitudinal curvature of the shank stiffener 14 of the last with which the unit is to be used and, in addition, the shank portions of the reinforcing piece and the insole are curved transversely to correspond to the transverse curvature of the bottom of the last. The shank stiffener 14 has a burr or spur 16 struck up from its rear portion and embedded within the material of the reinforcing piece 12 to assist in holding the shank stiffener in place and the forward portion of the shank stiffener is received within an opening in the form of an open notch 18 in the forward portion of the reinforcing piece so that it is positively maintained against lateral edgewise displacement.

As shown, the heel portion of the reinforcing piece 12 has substantially the same lateral edge contour as the heel portion of the insole but the shank portion of the reinforcing piece is substantially narrower than the shank portion of the insole so that marginal surfaces 20 of substantial width are exposed at the lower or lasting side of the insole for the reception of lasting cement in the process of cement lasting a shoe upper to the insole unit. The reduced or narrowed shank portion of the reinforcing piece 12, however, is substantially wider than the shank stiffener 14 and is so arranged that after cement attachment of the reinforcing piece to the insole the attached portions will be of sufficient width at opposite sides of the shank stiffener effectively to maintain the desired transverse curvature of the shank portion of the insole unit. Moreover, as shown, the opposite edges of the relatively narrow shank portion of the reinforcing piece are substantially perpendicular to its upper and lower surfaces so as to constitute substantially perpendicular lasting shoulders 22 for deflecting into upstanding positions the surplus lasting allowance of the upper and thereby facilitating the trimming of the latter. The reinforcing piece is beveled to a thin edge at its forward extremity which is located approximately at the break line of the insole. Forwardly and upwardly sloping beveled surfaces 23 are formed upon the heel portion of the reinforcing piece at opposite sides of the relatively narrow shank portion thereof to prevent the formation of any objectionable ridges in the over-lasting upper between those portions which are secured directly to the insole in the shank portion of the shoe and those which overlie the reinforcing piece at the heel of the shoe. The edges of the insole are shown as being beveled somewhat along its shank portion and around its heel end and the lateral edge of the heel portion of the reinforcing piece is beveled to blend with the bevel on the insole.

In making a shoe embodying the above-described insole unit, as shown in Fig. 4, the insole unit is assembled with a shoe upper 24 upon a last 26, the insole unit being tacked to the last bottom and the upper being worked over the last and having its margin secured in overlasted position upon the insole unit by means of cement. In Fig. 4 the lasting cement is indicated at 28. To hold the overlasted upper margins in place while the cement is setting tacks may be employed such as the lasting tacks 30, Fig. 4. In

the shank portion of the shoe bottom the surplus lasting allowance of the upper will be deflected upwardly while being wiped inwardly against the lasting shoulders 22 and thus caused to assume an upstanding position as indicated at 32 in Fig. 4. To assist in establishing this condition the tacks 30, as shown, are driven close to the lasting shoulders 22. After the lasting cement has set sufficiently to hold the upper securely in place the lasting tacks are withdrawn, and the surplus lasting allowance is trimmed. In the shank portion of the shoe the trimming of the upper is greatly facilitated by the fact that the surplus portions of the upper material are upstanding, as already described. Moreover, the upper is trimmed in the shank portion of the shoe so that its trimmed edges 34 are located closely adjacent to the edges of the reinforcing piece 12 and substantially flush with the outer surface of the latter and with the outer surface of the adjacent overlasted portions of the upper. Thus, the presence of the lasting shoulders 22 insures that, as a result of the lasting and trimming operations, a smooth bottom surface is provided to receive the outsole and one which is practically continuous from one lateral edge of the insole to the other in the shank portion of the shoe bottom.

After the upper has been trimmed it is only necessary to roughen the outer surface of the overlasted margins of the upper and coat them with cement in the usual way to prepare for the cement attachment of an outsole, such as the outsole 36, the margins at the attaching side of which have also been roughed and coated with cement. In accordance with the usual practice the cement coatings are applied to a quantity of outsoles and shoe bottoms before any of the outsoles are attached and a suitable solvent is employed to soften the cement just prior to the attachment of a particular outsole to a particular shoe. After the outsoles have been laid in place upon the shoe bottoms the attaching pressure is supplied by the use of a suitable sole-attaching press in a well-known manner.

Inasmuch as the reinforcing piece 12 has been made narrow enough in its shank portion to expose sufficiently wide areas of the insole surface at opposite sides of the reinforcing piece in the shank portion of the shoe bottom, the upper will be secured by cement directly to the leather insole itself in that portion as well as in the forepart of the shoe and there will be no danger that the attachment in the shank portion will subsequently become weakened as might happen if the upper were cement attached to a reinforcing piece of the customary laminated formation. Furthermore, the shank portion of the outsole will conform accurately to the transverse curvature of the last bottom, due to the facts that the outer surface of the overlasted upper in that portion of the shoe is substantially flush with the outer surface of the shank reinforcing piece and there are no spaces or cavities present between those surfaces.

Having described my invention, what I claim as new and desire to secure by Letters Patent of the United States is:

1. A reinforced shoe bottom unit comprising an insole having integral forepart, shank and heel portions, said shank portion being transversely curved to correspond to the transverse curvature of the bottom of a last, a heel and shank reinforcing piece located at the lower or lasting side of the insole, and a narrow

- shank stiffener strip interposed between said parts, said reinforcing piece having its heel portion of substantially the same lateral edge contour as the heel portion of the insole and having its shank portion substantially narrower than the shank portion of the insole and said shank portion having perpendicular edge faces extending throughout its entire length to constitute lasting shoulders, said reinforcing piece being secured by means of adhesive to the insole at both sides of the shank stiffener throughout areas of substantial width sufficient to maintain the transverse curvature of the insole, and said insole having marginal portions of its lower surface left bare throughout areas of substantial width at opposite sides of the reinforcing piece for the reception of lasting cement.
2. A reinforced insole unit comprising an insole, a reinforcing piece secured to the shank portion of the insole and having an opening in its forward portion, and a narrow shank stiffener strip interposed between said parts and having a forward portion retained against lateral edgewise displacement by engagement within said opening, said reinforcing piece being shaped to expose marginal insole surfaces of substantial width extending substantially throughout the length of the shank portion of the insole for the reception of lasting fastenings and having opposite edge faces perpendicular to its upper and lower surfaces providing lasting shoulders perpendicular to said exposed insole surfaces and extending substantially throughout the full length of the shank portion of the insole.
3. A shoe comprising, in combination, a relatively flexible insole, a relatively hard and stiff heel and shank reinforcing piece secured to the lasting side of the insole, and a shank stiffener interposed between said parts, said reinforcing piece covering the heel seat of the insole and extending forwardly to the ball portion thereof but having its shank portion substantially narrower than the shank portion of the insole and of uniform thickness throughout its width, an upper having marginal portions secured in overlasted positions upon the insole at opposite sides of the narrow shank portion of the reinforcing piece with their outer surfaces substantially flush with the outer surface of said reinforcing piece, and an outsole cement-attached to said surfaces of the overlasted upper.
4. A shoe comprising, in combination, an insole composed of relatively soft material to which lasting cement will readily adhere and having a transversely curved shank portion, a relatively hard and stiff heel and shank reinforcing piece secured to the lasting side of the insole and conforming in its shank portion to the transverse curvature of the shank portion of the insole, the reinforcing piece covering the heel seat of the insole and extending forwardly to the ball portion but being substantially narrower than the insole along the shank portion of the latter and having perpendicular edge faces along said narrower portion and an opening in its forward end portion, a narrow shank stiffener interposed between the insole and said reinforcing piece and having a portion received in said opening, an upper cemented to the margins of the insole at opposite sides of the narrow shank portion of said reinforcing piece and having its inner extremities abutting the perpendicular edge faces of said reinforcing piece, and an outsole cement-attached to the overlasted margins of the upper.
5. A shoe comprising, in combination, an insole composed of relatively soft material to which lasting cement will readily adhere, a relatively hard and stiff heel and shank reinforcing piece secured to the lasting side of the insole, the reinforcing piece covering the heel seat of the insole and extending forwardly to the ball portion thereof but being substantially narrower than the insole along the shank portion of the latter, a narrow shank stiffener interposed between the insole and the reinforcing piece, an upper having marginal portions secured in overlasted positions upon the insole at opposite sides of the narrow shank portion of the reinforcing piece, the outer surface of said overlasted upper portions being substantially flush with the outer surface of said reinforcing piece, and said overlasted upper portions having trimmed edges lying closely adjacent to the edges of said reinforcing piece and substantially flush with the outer surface of the latter, and an outsole cement-attached to said outer surface and to said trimmed edges.
6. That improvement in methods of making shoes which consists in assembling with an upper on a last an insole unit comprising an insole having exposed marginal lasting surfaces of substantial width in its shank portion and a shank reinforcing piece the opposite lateral edges of which constitute substantial perpendicular lasting shoulders extending along the inner boundaries of said insole lasting surfaces, lasting the upper over said insole lasting surfaces and against said shoulders and securing it in overlasted position upon the insole with surplus portions of its lasting allowance upstanding beside said shoulders, trimming said surplus lasting allowance substantially flush with the exposed surface of said reinforcing piece, and laying an outsole and securing it by means of cement to said overlasted portions of the upper including said trimmed edges thereof.

CLIFFORD ROBERTS.
